(57) **CLAIM**

The ornamental design for a mirror, as shown and described.

DESCRIPTION

FIG. 1 is a perspective view of the mirror of the present invention;

FIG. 2 is a front view of the mirror of FIG. 1;

FIG. 3 is a rear view of the mirror of FIG. 1; and,

FIG. 4 is a top view of the mirror of FIG. 1.

The mirror of the present invention is symmetrical and the top, bottom and side views are identical.

1 Claim, 2 Drawing Sheets

FIG. 3

FIG. 4
